THERAPEUTIC LAMP

Irving Naxon, Chicago, Ill.

Application July 21, 1958, Serial No. 51,865

Term of patent 14 years

(Cl. D48—20)

Fig. 1 is a front elevational view of a therapeutic lamp showing my new design with portions of the base omitted for convenience of illustration;

Fig. 2 is a side elevational view thereof, the other side being substantially the same; and

Fig. 3 is a vertical section taken through the casing member as illustrated in Fig. 1.

The dominant features of my design reside in the portions shown in full lines.

I claim:

The ornamental design for a therapeutic lamp, as shown and described.
